UNITED STATES PATENT OFFICE.

JOHN C. DOLGONAS, OF CHICAGO, ILLINOIS.

GAME APPARATUS.

Application filed May 25, 1922. Serial No. 563,519.

To all whom it may concern:

Be it known that I, JOHN C. DOLGONAS, a citizen of United States, residing at Chicago, in the county of Cook, State of Illinois, have invented certain new and useful Improvements in Game Apparatus; and I do hereby declare the following to be a full, clear, and exact description of the invention, such as will enable others skilled in the art 10 to which it appertains to make and use the same.

The object of the invention is to provide a game apparatus of the type in which a projector or missile of the rolling type such 15 as a marble or the equivalent thereof is employed and which is adapted to be manually projected under conditions involving a display of accuracy or marksmanship in an effort to count by causing the said object to 20 enter one or another of a series of openings in an enclosure affording access to a plunger or baffle, by means of which a movable figure representing an object may be displaced to serve as an indicator of the effect of the 25 operator's shot or stroke, and in this connection to provide an apparatus affording protection to the objective figures or indicators while enabling the effect of the shot or stroke 30 of the operator to be readily noted; and with these objects in view, the invention consists in the construction, combination and relation of parts of which a preferred embodiment is shown in the accompanying drawings, wherein,

35 Figure 1, is a perspective view,
Figure 2, is a longitudinal section, and
Figure 3 is a plan view of an apparatus embodying the invention.

The device consists essentially of a box or 40 casing 10, having in its front wall a series of entrances or openings 11 of a size adapted to receive a marble or like rolling, preferably spherical, object 12, and provided at its rear end with a platform 13 upon 45 which are hingedly mounted indicating objects or figures 14 of any preferred or desired configuration or design, such as men, animals or the like, which when in the upright position indicated by the full lines 50 in the drawings are screened or protected from the front by the box or casing.

Within the box or casing, in relation to 55 each of the entrance openings which correspond in number with the indicating objects at the rear, are mounted the sliding follower rods 15, fitted near their front ends in

hangars 16 and at their rear ends in openings 17 in the rear wall of the casing, said follower rods respectively carrying baffle plates or heads 18, which are respectively disposed in spanning relation with the openings in the front wall and obstruct the entrance of the marble therethrough, to the end that a marble or like rolling object projected toward the box or casing and entering one of said openings, will come in contact with the baffle plate or head of the follower rod related with opening and impart a rearward impulse to the rod to bring its rear end into contact with the corresponding indicating objective at the rear end of the casing, with the result of moving the latter from upright to a reclining or horizontal position, as indicated by the dotted lines in the drawing, provided the impulse imparted to the follower rod has been sufficient.

It will be understood that the resistance offered to the sliding movement of the follower rods may be variously modified or controlled by friction or otherwise, and the indicating objects as illustrated are provided with bases 19 normally resting upon the platform 13 and serving as a means of giving a reasonable amount of stability to the figures to yieldingly hold them in the normal or upright position.

In operation the casing is disposed between the player and the indicating objects, which to increase the interest in the game may have numerical designations which may be agreed upon mutually by the opponents to determine superiority in the game, so that only by causing the rolling object to enter one of the openings provided in the front of the casing can the indicating object be thrown to a position entitling the player to a mark or count.

Obviously the parts may be reset by manually restoring the indicating object to the upright position and accordingly advancing the follower rod to cause its head or the baffle plate to resume a position obstructing the entrance through the corresponding opening.

Claims:

1. A game apparatus having a casing provided in its front wall with entrance openings, a platform externally of the rear wall of the casing, indicating objects hingedly carried by the platform at the rear of and screened by the casing, hangers in the casing, and slidably follower rods mounted in

105

100

110

the hangers with their rear ends in operative relation with said indicating objects and provided at their front ends with heads or baffle plates spaced inwardly of and normally obstructing the several entrance openings.

2. A game apparatus comprising a box having an opening in its front wall and through which a game piece is adapted to be projected, a target movably mounted rearwardly of the rear wall of the box and movable toward and away from the rear wall thereof, a rod slidable through the rear wall

of the box and in position to move the target away from said rear wall, a hanger in the box adjacent the said opening and slidably receiving the rod, and a transverse head on the end of the rod inwardly of the opening for engagement by a game piece for movement of the rod into target striking position. 20

In testimony whereof, I affix my signature, in the presence of two witnesses.

JOHN C. DOLGONAS.

Witnesses:

R. J. FITZGERALD,
CHARLES BUCHHOLZ.
